UNITED STATES PATENT OFFICE.

FRANK KRAEMER, OF LOS ANGELES, CALIFORNIA, ASSIGNOR TO SUN-RAY WORKS, INC., A CORPORATION OF CALIFORNIA.

WATER PURIFIER.

Application filed December 3, 1923. Serial No. 678,144.

To all whom it may concern:

Be it known that I, FRANK KRAEMER, a citizen of the United States, residing in the city of Los Angeles, county of Los Angeles, and State of California, have invented certain Improvements in Water Purifiers, of which the following is a specification.

My invention relates to water purifiers, and more particularly to electric apparatus 10 adapted for use in causing the precipitation of certain of the foreign matter in water without destruction of the organic matter, the object of the invention being to provide a device which is automatic in the regulation 15 of the heat developed and thus avoiding the overheating or cooking action which is caused thereby.

In order to fully explain my invention, I have shown one practical embodiment there- 20 of on the accompanying sheet of drawings, which I will now describe.

Figure 1 is a side elevation of a container for water with my invention applied thereto, the same being connected with the usual 25 electric connection;

Figure 2 is a vertical sectional view through the invention illustrated;

Figure 3 is a top plan view of the same;

Figure 4 is a cross sectional view taken on 30 line 4—4 of Fig. 2; and

Figure 5 is an enlarged view of one of the thermostat supports for the electrodes.

Referring more in detail to the invention as here illustrated, 1, designates a head piece 35 of any suitable insulating material, adapted to have placed thereon the open end of a cylindrical tube, 2, preferably made of aluminum and being perforated or provided with the holes 2^a in its side, the lower end of said 40 tube being open also and being capable of being removed from the head member 1. The head member 1 may be so made as to form the cap or cover for a container, as 3, when placed therein, as indicated in Fig. 1. 45 The head member is open in its center and is provided with two thermostatic supports, as 4 and 5, made of two kinds of metal of different expanding qualities, such as brass and steel, soldered or welded or even riveted 50 together, as indicated in Fig. 5, wherein the two metals, 4^a and 4^b, are shown composing the member 4. The upper ends of said supports 4 and 5, are secured to the head piece 1 as by means of bolts 6, 6, which constitute 55 terminals to have attached thereto the wires,

7, 7, from any source of electric energy. To the lower ends of said supports, 4 and 5, are suspended two metallic electrodes, 8 and 9, preferably of aluminum and of angular or channel iron form and having their lower 60 ends bent to an angle toward each other and arranged in such relationship to each other that they will, when together, overlie one over the other, and yet be free to move apart under the expansion of their supporting members 4 and 5, in the manner indicated in Fig. 2 by the dotted line positions.

When the terminals or electrodes are moved apart in the manner indicated by the dotted line positions, the greater is the 65 resistance from the water which makes the circuit connection from one electrode to the other, and the closer the electrodes are together, the less is the resistance. In one case the heat is increased and in the other it 70 is reduced. The more resistance there is from the water the less amperage there is and consequently less heat. Thus by this 75 automatic action of the movement of the electrodes the degree of heat applied to the 80 water is regulated and automatically controlled, and overheating is avoided.

By actual tests of water taken from the same source and divided into two parts and one 85 part tested or treated with my device for a short time, the device being adapted to develop approximately 140 degrees, with an alternating current at 110 volts, the result showed permanent hardness 44 parts per million, temporary hardness 150 parts per 90 million, or a total of 194 parts, as against 62, 200, or a total of 262 parts per million before treating. It also showed 20.58 total solids after treating as against 26.02 total 95 solids before treating. Total incrusting solids 10.07 after treating, as against 14.39 total incrusting solids before treating.

I am aware that many changes in details can be made in the invention without departing from the spirit thereof, and I do 100 not, therefore, limit the invention to the details showing, except as I may be limited by the hereto appended claims.

I claim:

1. In a device of the character referred to, 105 two electrodes, a head for supporting the same, thermostatic supports for said electrodes interposed between said head and said electrodes and adapted to move the same toward and from each other as said thermo- 110

static supports contract and expand, and means for connecting a source of electric energy to said supports and electrodes.

2. In a device of the character referred to, 5 in combination, two aluminum electrodes, having their free ends bent toward each other to overlap each other, one above the other, a thermostatic support for each of said electrodes, said supports being each 10 made of two different metals of different expanding properties, means for connecting a source of electric energy to said supports, and means for supporting said device in water, substantially as and for the purpose 15 described.

3. In combination with a container of 20 water, means for purifying said water, said means comprising two electrodes adapted to be extended down into said water, a thermostatic support for each of said electrodes, and means for connecting a source of electric energy to said thermostatic supports, whereby said electrodes are automatically moved toward and from each other substantially as and for the purpose described. 25

4. In combination with a container of 30 water, means for purifying said water, said means comprising a head, two electrodes suspended therefrom, thermostatic supports connecting said electrodes to said head, said electrodes having portions adapted to over-

lap each other as they are moved toward and from each other, and a cylindrical member around said head and said electrodes and open to receive water therein, substantially 35 as described.

5. A device of the character referred to comprising in combination with a container, a head member adapted to fit said container as a cover therefor, two metallic electrodes 40 having angle portions positioned to overlap each other, thermostatic supports connecting said electrodes to said head member, means for connecting a source of electric energy to said supports, and a surrounding enclosure 45 member around said electrodes and open to permit access of water thereto when placed in said container, substantially as shown.

6. The method of purifying water which consists in inserting therein two electrodes 50 supported by thermostatic supports to be automatically moved toward and from each other to automatically increase or reduce the water resistance for current passing from one electrode to the other as the heat generated by said current increases or decreases, and supplying electric current to said electrodes, substantially as herein described. 55

Signed at Los Angeles, Los Angeles County, California, this 26th day of November, 1923. 60

FRANK KRAEMER.
